UNITED STATES PATENT OFFICE.

GIBSON H. DAWSON, REUBEN C. NORTON, AND ISRAEL SHOUDY, OF
ROCKFORD, ILLINOIS.

DESIGN FOR A GRAVE-MARKER.

SPECIFICATION forming part of Design No. 35,121; dated September 17, 1901.

Application filed August 1, 1901. Serial No. 70,561. Term of patent 7 years.

To all whom it may concern:

Be it known that we, GIBSON H. DAWSON, REUBEN C. NORTON, and ISRAEL SHOUDY, citizens of the United States of America, residing at Rockford, in the county of Winnebago and State of Illinois, have invented and produced a new and original Design for Grave-Markers, of which the following is a specification, reference being had to the accompanying drawing, forming part thereof.

The figure is a front elevation of a grave-marker, showing our new design.

As shown in the drawing, the leading or material features of our design consist of an open hand with the palm turned outward, having a heart resting therein and three con-

nected chain-links extending across the wrist thereof.

Having described our invention, what we claim as new, and desire to secure by Letters Patent, is—

The design for a grave-marker, as herein shown and described.

In testimony whereof we have signed our names to this specification in the presence of two subscribing witnesses.

GIBSON H. DAWSON.
REUBEN C. NORTON.
ISRAEL SHOUDY.
